5 Claims. (Cl. 60—39.28)

1

This invention relates to means for controlling the supply of liquid fuel to an internal combustion prime mover, such as a jet-propulsion engine, gas turbine or the like, and to which air is supplied by a blower.

The object of the invention is to provide improved means whereby variation in the ratio of the rate of fuel and air supply can be effected in response to variation of the blower delivery pressure.

In the accompanying sheets of explanatory drawings—

Figure 1 is a part sectional view illustrating diagrammatically fuel controlling means in accordance with the invention applied to a variable delivery fuel pump of the swash plate type.

Figures 2 and 3 are similar views to Figure 1 illustrating respectively two modified forms of the invention.

Figures 4 and 5 are sectional views drawn to a larger scale than Figure 1 and illustrating respectively two modified details.

The variable delivery pump shown in Figure 1 is of well known form and comprises a rotary body part *a* in a casing *b*, a plurality of spring loaded plungers *c* mounted in bores in and extending from one end of the body part, an angularly adjustable swash plate *d* by which the plungers are actuated during rotation of the body part, a fuel inlet passage *e*, and a fuel delivery passage *f*. The body part *a* is adapted to be driven in any convenient manner by the prime mover (not shown) to be supplied with fuel by the pump, the prime mover being supplied with air by a blower (also not shown).

At one end of the pump casing *b* is a cylinder *g* having closed ends. Within the cylinder *g* is arranged a piston *h* loaded by a spring *i*, and extending from one side of this piston and through one end of the cylinder is a rod *j* which is connected to the swash plate *d*. One end of the cylinder *g* is in free communication with the pump delivery passage *f* through a passage *k*. The other end of the cylinder *g* (which contains the spring *i*) communicates with the pump delivery passage *f* through a restricted passage *m*, and also communicates with a small vent *n* which at its outer end forms a seating for a valve *o* on one end of a lever *p* in a chamber *q*. The spring *i* is arranged to urge the piston *h* in a direction for moving the swash plate *d* to a position corresponding to maximum pump output. When the vent *n* is closed by the valve *o* on lever *p* the liquid fuel pressures on the two sides of the piston *h* will be approximately equal.

2

ized and the piston will take up a position determined by the additional force exerted by the spring *i*. When the vent *n* is opened, liquid will leak away from the underside of the piston *h* and will not be replaced at an equal rate due to the restriction *m*, whereby the liquid pressure beneath the piston is reduced and the liquid pressure above the piston will cause it to move downwardly against the loading spring *i*, thereby displacing the swash plate *d* to reduce the pump output.

The delivery passage *f* is formed with an enlargement *r* through which fuel can flow to the nozzles *s* of the prime mover under the control of a valve *t* adapted to co-operate with an annular seating *u* in the enlargement. The extent of opening of the valve *t* depends in known manner upon the pump delivery pressure.

In carrying the invention into effect as shown in Figure 1, the valve lever *p* is adapted to be moved against the action of a loading spring *v* in the direction for opening the vent *n* by an evacuated and deformable capsule *w*, and also by a piston *x*.

25 The capsule *w* is arranged in a chamber *z* to which air delivered by the blower can be admitted through an inlet *2*, and is adapted to exert pressure on the valve lever *p* through the medium of a stem *3* extending through one end of the chamber, the arrangement being such that the pressure exerted by the capsule on the valve lever decreases with increase in the pressure of the blower-air.

The piston *x* is movable in a cylinder *4* under 35 the action of fuel delivered by the pump to exert pressure on the valve lever *p* through the medium of a rod *5*. One end of the cylinder *4* is connected by a passage *6* to a second passage *7* at a position between two restricted orifices 40 *8*, *9* in the second passage. At one end the second passage *7* is in communication with the pump delivery passage *f*. The other end of the second passage *7* is open and is controlled by a valve *10* on one end of a lever *11*, the latter 45 being situated in a chamber *12*, and being loaded by a spring *13* in the direction for closing the valve.

The valve lever *11* is movable in the direction for opening the valve *10* by a diaphragm *14* which is adapted to act on the valve lever through the medium of a stem *15*, and which divides a chamber *16* into two compartments *17*, *18*, the compartment *17* being adapted for connection by a passage *19* to the inlet side of the blower, and the other compartment *18* being adapted for

connection by a passage 20 to the delivery side of the blower. The compartment 18 contains an evacuated and deformable capsule 21 which is connected at one end to the diaphragm and at the other end to the adjacent wall of the chamber 16.

The arrangement is such that so long as the ratio of blower outlet and inlet pressures lies below a predetermined amount, the valve 10 controlling the second passage 7 remains closed, and the vent-controlling valve σ is then responsive to the blower air pressure and the full pressure of the fuel delivered by the pump. But when the ratio of blower outlet and inlet pressures exceeds the predetermined amount, the valve 10 controlling the second passage 7 is opened, and the vent-controlling valve σ is then subject to the blower air pressure and a fuel pressure lower than the delivery pressure of the pump.

The modification shown in Figure 2 differs from that shown in Figure 1 in the following respects:

The pump delivery passage f is controlled by a throttle 22 connected to an evacuated and deformable capsule 23 in a chamber 24 to which air delivered by the blower can be admitted through an inlet 25, so that the throttle is responsive to blower air pressure. Also the pump delivery passage f is connected by a passage 26 at the exit side of the throttle 22 to the chamber 12 containing the valve lever 11 above mentioned. Moreover, the chamber 12 and the part of the above mentioned passage 7 between the restricted orifices 8, 9 are connected by passages 27, 28 to opposite ends of the cylinder 4 containing the piston x . Further, the vent-valve lever p is movable in the direction for opening the vent n solely by the piston x . In other respects the example shown in Figure 2 is similar to that shown in Figure 1 and is indicated by the same reference characters.

When the valve 10 controlling the passage 7 is closed, the piston x (and consequently the vent-valve lever p) is subject to the full difference of the fuel pressures at opposite sides of the throttle 22. But when the valve 10 is open, the piston x is subject to a lower difference of fuel pressure.

The modification shown in Figure 3 differs from that shown in Figure 2 in the following respects:

The vent-valve lever p is connected to a pair of coaxial integral or interconnected pistons 30, 31 of different diameters contained in a stepped cylinder 32. The two ends of the larger part and the outer end of the smaller part of the stepped cylinder 32 are respectively connected by three passages 33, 34, 35 to a cylinder 36 containing a sliding piston valve 37 which is connected to the diaphragm 14. The cylinder 36 is also connected by a pair of passages 38, 39 to the pump delivery passage f at opposite sides of the throttle 22. In other respects the example shown in Figure 3 is similar to that shown in Figure 2 and is indicated by the same reference characters.

The arrangement is such that in one position of the piston valve 37 the lower side of the larger piston 31 is exposed to the fuel pressure at the upstream side of the throttle 22 while the upper side of the smaller piston 30 is exposed to the fuel pressure at the downstream side of the throttle and in another position of the piston valve the smaller piston 30 is exposed at opposite sides respectively to the said pressures, both

sides of the larger piston being at this time exposed to the pressure at the upstream side of the throttle.

In any of the examples above described the evacuated and deformable capsule 21 may be directly connected at its opposite ends respectively to the diaphragm 14 and the adjacent wall of the chamber 16 or 41 as shown in Figure 4 or Figure 5. In the example shown in Figure 4 the chamber 16 is of uniform diameter, and is provided with inlets 19, 20 as previously described through which the opposite sides of the diaphragm 14 are respectively exposed to the inlet and outlet pressures of the blower. If, however, it is desired to avoid exposure of the capsule 21 to the delivery pressure of the blower, the diaphragm 14 may serve with another diaphragm 40 to divide a chamber 41 into three compartments 42, 43, 44 as shown in Figure 5. The compartment 44 is smaller than the other compartments, and contains the capsule 21, the latter being connected at its opposite ends respectively to the diaphragm 14 and the adjacent end wall of the chamber 41. Also this compartment 44 and the compartment 42 are situated at opposite ends of the chamber 41, and are adapted for connection by passages 45 to the inlet side of the blower. Moreover, the compartment 43, which is situated between the other compartments 42, 44, is of the same diameter as the compartment 42, and is adapted for connection by a passage 46 to the outlet side of the blower.

By this invention the ratio of the fuel and air supplied to the prime mover is variable in response to predetermined changes in the blower air pressure.

The invention is not, however, limited to the examples described as subordinate constructional details may be varied to suit different requirements. Thus diaphragms may be used instead of pistons or deformable capsules, and vice versa, for actuating the various valves.

Having thus described my invention, what I claim as new and desire to secure by Letters Patent is:

1. For use in controlling the supply of fuel from a pump to a prime mover which receives air from a blower, a controlling means comprising, in combination, a fluid pressure operable device for regulating the rate at which fuel is supplied to the prime mover, a first valve controlling said device, a second device operable by fuel pressure delivered by the pump for actuating the said valve to reduce the fuel supply as the pump pressure rises, a first means responsive to the pressure of air from the blower for varying the effect of the second device on the first valve to increase the fuel supply when the blower pressure increases and vice versa, a second valve for varying the action of the fuel pressure from the pump on the second device, and a second means responsive to the blower inlet and outlet air pressures for actuating the second valve to reduce the fuel pressure acting on the second device and thereby increase the supply of fuel when the ratio of blower outlet and inlet pressure exceeds a predetermined ratio, and vice versa.

2. A controlling means according to claim 1, comprising a passage through which fuel can flow under the control of the second valve, two flow restricting means in said passage, and a connection between a point intermediate said restricting means and one end of the second

device whereby the pressure at said point is effective on the said second device.

3. A controlling means according to claim 1, comprising a delivery passage through which liquid fuel from the pump can flow, a throttle responsive to blower-air pressure for controlling fuel flow through said delivery passage and forming a part of the first means, a second passage communicating with the said delivery passage at the entrance side of the throttle and controlled by the second valve, two flow restricting means in the second passage, a connection between a point intermediate said restricting means and one end of the second device whereby the pressure at said point is effective on said second device, and a connection between the other end of the second device and the delivery passage at the exit side of the throttle.

4. A controlling means according to claim 1, comprising a stepped cylinder forming a part of the second device, a pair of coaxial pistons of different diameters slidable in the cylinder and forming another part of the second device, a second cylinder containing the second valve, the latter having the form of a piston valve, three

passages connecting different parts of the stepped cylinder to the second cylinder, a delivery passage through which liquid fuel from the pump can flow, a throttle responsive to blower-air pressure for controlling the fuel flow through the delivery passage and forming a part of the first means, and additional passages connecting the second cylinder to the delivery passage at opposite sides of the throttle.

5. A control means according to claim 1, in which the means for actuating the second valve comprise, in combination, at least one diaphragm arranged to divide a chamber into parts, connections between said parts and the inlet and outlet respectively of the blower, and an evacuated and deformable capsule in the chamber and connected to the diaphragm.

OWEN NAPIER LAWRENCE.
